UNITED STATES PATENT OFFICE.

JOHN P. MURRAY, OF WASHINGTON, DISTRICT OF COLUMBIA.

TYPOGRAPHICAL MACHINE.

Application filed July 17, 1923. Serial No. 652,168.

(GRANTED UNDER THE ACT OF MARCH 3, 1883; 22 STAT. L. 625.)

To all whom it may concern:

Be it known that I, JOHN P. MURRAY, a citizen of the United States, and resident of Washington, in the District of Columbia, have invented certain new and useful Improvements in Typographical Machines, of which the following is a specification.

The invention described herein may be used by the Government of the United States or any of its officers or employees, or by any other person in the United States in the prosecution of work for the Government, without the payment of any royalty thereon.

This invention is an improvement in typographical machines designed more particularly for printing matter where considerable space is desired between the lines of reading, such as legislative documents, although its use is not limited to such documents.

In the printing of some classes of documents, such as bills introduced into the Congress of the United States, it is desirous that the lines of printed matter be spaced relative to each other to permit of notations or the insertion of amendatory matter to the printed text. Furthermore, after a bill or resolution shall have been introduced into the legislative body, it is desirous that printed copies thereof be available as soon as possible. For that reason the subject-matter of such documents is usually set into type by type-setting machines, such for example as the well known linotype machines wherein the reading matter is cast in separate lines as distinguished from single letters or in large cast forms.

In practice, after the subject-matter has been set into type it has heretofore been necessary to have the printer manually insert spacing elements or "leads" between the lines of type and thereafter take proof copies before the matter is finally printed.

The invention aims to quickly set into type the subject-matter to be printed and to promptly produce the printed copies by forming on the metal "slug" or line of type spacing elements of the width required in the form. The new line of type thus produced effects a saving in the weight of the form and also a saving in the time and labor of the printer who was formerly required to separately handle each spacing element or "lead" to be placed between the lines of type.

In accomplishing this new result the invention comprises the method and means whereby a cast metal element forming a line of type may be provided with a spacing element integral therewith serving as a means to produce lines of printed matter which may be variously spaced relative to each other, the spacing between the lines of printed matter being determined by the rib on the slug of type, the depth of the rib on the slug depending of course upon the depth of the recesses in the mold, and this is determined by the space desired between the lines of printed matter.

To enable those skilled in the art to more fully understand the invention, a practical embodiment of the mold elements and of the product is illustrated in the accompanying drawings, wherein—

Figure 1 is a front elevation of the mold with the usual elevator jaw in operative position thereon.

Figure 2 is a similar view of the mold with the elevator jaw removed and disclosing the depth of the recesses to form the spacing ribs on the slug or line of type.

Figure 3 is a rear elevation of the mold shown in Figure 2.

Figure 4 is a top plan view of the base or fixed section of the mold showing the removable spacing blocks partly advanced.

Figure 5 is a bottom plan view of the mold cap or removable section disclosing the spacing rib recesses formed therein.

Figure 6 is an end view of the mold looking at the left end as illustrated in Figure 2.

Figure 7 is a rear elevation of the elevator jaw, the front view of which is illustrated in the assembly view of Figure 1.

Figure 8 is a sectional view through the elevator jaw of Figure 7.

Figure 9 is a perspective view of one of the spacing blocks to mount the removable web-forming member of the mold.

Figure 10 is a front elevation of a line of type as produced by the mold, the illustration disclosing the printing face of the slug of type and a plurality of ribs in rear of the printing face.

Figure 11 is a plan view of the rib-formed face of the slug of type of Figure 10.

Figure 12 is a front elevation of the printing face of the slug of type as it would

appear if molded by the matrices without the various changes and improvements of the mold devices described herein.

Figure 13 is a rear elevation of the slug 5 of type illustrated in Figures 10 and 11, disclosing the saving in metal to lighten the weight of the set up form.

In producing the improved slug or line of type it has been found desirable to make 10 some changes in the casting mechanism of the ordinary linotype machine. Certain parts of the machine containing the changes necessary are illustrated in the accompanying drawings. The usual mold is shown in 15 Figures 1, 2 and 3, wherein is illustrated the fixed element 1 and the mold cap or removable section 2. The fixed element 1 is provided with the usual liner blocks 3 slidably mounted thereon, but in carrying out 20 the invention it has been found desirable to provide these liner blocks with a recess 4 to receive an extension 5 which has been added to the usual elevator jaw 6.

The mold cap or removable section 2 of 25 the mold is provided with a plurality of mold recesses 7 opening into the usual mold space 8 which produces the slug or line of type. These recesses 7 may be made of varying depth on separate mold caps 2 to provide ribs of the desired length to correspond 30 to the width or depth of the "lead" or separate spacing element which these ribs replace and serve to produce a slug or line of type having spacing ribs integral therewith 35 as shown in Figures 10, 11 and 13. If desired, the removable section or mold cap 2 may be set back as at 9 to facilitate the mounting of the elevator jaw 6 and its extension 5 on the mold.

40 The matrices M now used in printing legislative documents such as bills and resolutions before the Congress of the United States, are provided with two dies, one to form the ordinary printed letter as indicated at 22 in Figure 12, and the other die to form a letter with the addition of a horizontal line through the same as shown at 45 23 in Figure 12. The deformed letters 23 produce words with a line drawn through 50 them to indicate the deletion of such words in the text. If a slug is cast with the mold and elevator jaw 6 constructed as ordinarily used, the slug would have the two printing faces as disclosed in Figure 12. Accordingly, the elevator jaw 6 is provided with 55 an extension 5 (see Fig. 6) designed to block off one or the other, 22 or 23, of these lines of printing face and to produce a deformed slug such as is shown at 14 in Figures 10, 60 11 and 13. Moreover, the mold cap 2 may be so constructed that the slug or line of type 15 will have a broad printing web 24, a thinner narrow body 25, and the spacing ribs 15 integral with the printing web and 65 body. The saving of metal in the body or

slug lightens the weight of the slug so that it, with the addition of its ribs 15, is of substantially the same weight or possibly but slightly in excess of the weight of an ordinary slug without the spacing ribs 15. 70

This saving in weight is found of advantage in assembling a series of ribbed slugs into a form where the spacing ribs integral with the slugs save the weight of the "leads" formerly used. Besides, the time of the 75 operator is saved in that no type "leads" are now necessary to be inserted by hand as was formerly, to produce the spaced relation between the lines of printed matter.

It will be observed that the new slug of 80 type is formed by flowing molten type metal through the mold and the recesses 7 of the mold cap 2 into contact with a single type face of a plurality of matrices presented to the mold.

Having thus described my invention, what I claim as new is—

1. In a type machine comprising casting mechanism and manually-controlled matrices, means to cast a line of type provided with spacing elements integral therewith to print lines of subject-matter in spaced relation to each other without the interposition of separate spacing type leads, such means comprising a mold cap provided with 90 a plurality of rib-forming recesses, and an elevator jaw having type-mold controlling means for withholding the flow of type-metal to a part of the matrices presented to the mold. 95

2. In a type machine comprising casting mechanism and cooperating matrices, means to cast a line of type provided with spacing elements integral therewith, whereby such line of type may be assembled to print lines 100 of subject-matter variously spaced relative to each other and thereby omit the interposition of spacing type-leads between the lines of type, such means comprising a mold cap having a plurality of rib-forming 105 recesses and an elevator jaw provided with a type-metal controlling extension for limiting the flow of metal to a part of the matrices. 110

3. In a type machine comprising casting mechanism and cooperating matrices, means to cast a deformed line of type by providing a type slug with spacing elements integral therewith to operate as type-spacing leads between lines of type, such means comprising a mold cap having a plurality of rib-forming recesses, an elevator jaw having type-metal controlling means cooperating 115 with the rib-forming recesses of the mold cap, and recessed liner blocks to space the elevator jaw relative to the mold cap and the matrices presented to the mold. 120

4. In a type machine comprising casting mechanism and manually-controlled matrices, means to cast lines from matrices 125 130

- having a plurality of casting faces wherein but one casting face is presented to the mold and to provide the linotype with elongated spacing ribs for the purpose of printing the 5 subject matter in spaced relation without the interposition of separate spacing type leads, such means including an elevator jaw having a type mold controlling member depending therefrom to limit the flow of metal to 10 one casting face of the matrices, and spacing blocks provided with means cooperating with the depending member of the elevator jaw for the purpose of controlling the flow 15 of casting material.
- 15 5. In a type machine comprising casting mechanism and manually-controlled matrices, means to cast lines from matrices having a plurality of casting faces wherein but one casting face is presented to the mold 20 and to provide the linotype with elongated spacing ribs for the purpose of printing the subject matter in spaced relation without the interposition of separate spacing type leads, such means including an elevator jaw 25 having a type mold controlling member depending therefrom to limit the flow of metal to one casting face of the matrices, and interchangeable spacing blocks provided with recesses to cooperate with the depending 30 member of the elevator jaw to cast lines of type of varying points or widths by regulating the flow of casting metal.
6. In a type machine comprising casting mechanism and manually-controlled matrices, means to cast a linotype provided with 35
- elongated spacing elements integral therewith to print lines of subject matter in spaced relation to each other without the interposition of separate spacing type leads, such means comprising a mold and a mold 40 cap provided with elongated rib-forming recesses in said cap, interchangeable spacing blocks of varying widths adapted to be interposed between the mold and cap, and an elevator jaw having a depending metal controlling extension to limit the flow of metal to a portion of the matrices, said extension being mounted upon a recessed portion of the liner blocks. 45
7. The method of producing a line of type 50 having a printing face, a body of less thickness than the printing face and elongated spacing ribs extending beyond the width of the printing face to thereby print subject matter in spaced relation without the interposition of separate spacing type leads, which comprises flowing molten type metal through a mold having elongated recesses and into contact with one part of the matrices presented to the mold, and limiting the 55 flow of molten type metal to the remainder of the faces of the matrices by the interposition of a depending section of an elevator jaw which regulates the width of the printing face of the type slug, and permitting the 60 molten type metal to cool while in contact with the mold, the matrices and the depending section of the elevator jaw. 65

JOHN P. MURRAY.
